UNITED STATES PATENT OFFICE.

FLORENCE M. I. REEVE, OF ELBOW LAKE, MINNESOTA.

STRAINER.

No. 892,551.

Specification of Letters Patent.

Patented July 7, 1908.

Application filed October 11, 1907. Serial No. 397,018.

To all whom it may concern:

Be it known that I, FLORENCE M. I. REEVE, a citizen of the United States, residing at Elbow Lake, in the county of Grant 5 and State of Minnesota, have invented a new and useful Strainer, of which the following is a specification.

This invention relates to domestic strain- 10 ers and has for its object to provide a com- paratively simple and inexpensive device of this character especially designed for straining milk and which also may be used for straining fruit, syrup and the like when mak- ing jelly.

15 A further object of the invention is to provide a strainer including an open ended receptacle or rim having a clamping band associated therewith for retaining the straining medium in position on the bottom of the 20 receptacle whereby the same may be readily removed and cleaned when necessary.

25 A further object is to form the rim with laterally extending arms which, in conjunction with the operating handle serves to support the strainer in position on a bucket, 25 tub or other suitable receptacle during the straining operation.

30 A still further object of the invention is to generally improve this class of devices so as 35 to increase their utility, durability and efficiency as well as to reduce the cost of manufacture.

Further objects and advantages will appear in the following description, it being 35 understood that various changes in form, proportions and minor details of construction may be resorted to within the scope of the appended claims.

In the accompanying drawings forming a 40 part of this specification: Figure 1 is a top plan view of a strainer constructed in accordance with my invention showing the same supported in position on a receptacle. Fig. 2 is a transverse sectional view taken on 45 the line 2—2 of Fig. 1. Fig. 3 is a perspective view of the clamping band and its associated parts detached from the supporting rim.

Similar numerals of reference indicate cor- 50 responding parts in all of the figures of the drawings.

The improved device forming the subject matter of the present invention includes an open ended receptacle or annulus 5 prefer- 55 ably formed of sheet metal and having its up-

per and lower edges bent laterally to form reinforcing beads 6 and 7.

Extending transversely across the bottom of the rim or annulus 5 is a strip of muslin, cheese-cloth or other suitable fabric 8 which 60 constitutes the filtering medium and which is retained in position on the rim 5 by means of a clamping band 9. The clamping band 9 is preferably formed of a single strip of metal having its adjacent end over-lapped and pro- 65 vided with reinforcing brackets 10 terminat- ing in angularly disposed ears 11. Secured to one of the ears 11 is a threaded pin 12 which extends through an opening in the ad- jacent ear and receives a wing nut 13 so that 70 by adjusting the nut on the pin the ears may be drawn together thereby to clamp the band in engagement with the filtering medium and thus retain the latter in position on the annu- lus or rim. 75

The split clamping band 9 is reinforced and strengthened by the provision of longitudinal rods or wires 15 which curve to conform to the shape of the band and have their intermediate portions soldered or otherwise rigidly secured 80 thereto, as shown. One end of each rod or band 15 is bent laterally to form an angularly disposed supporting finger 16 while the oppo- site ends of the rods are united and extended rearwardly to form a shank 17 which enters 85 the longitudinal bore of an operating handle 18. It will thus be seen that the arms 16 in conjunction with the operating handle 18 serve to support the strainer in position on a bucket, pail, tub or other suitable receptacle 90 during the straining operation. It will also be observed that the rods 15 not only serve to reinforce and strengthen the band 9 but by reason of their peculiar shape serve to exert a 95 spring action on the split portion of the band and thus assist in retaining said band in position on the rim or annulus.

In using the device for straining milk or jelly the cheese cloth or other flexible medium is extended across one end of the rim or 100 annulus 5 after which the clamping band is placed over the exterior walls of the rim and forced in engagement with the lower annu- lar bead 7, the wing nut 13 being subsequently 105 adjusted so as to clamp the filtering medium in position on the rim. The strainer is then inverted and placed in position on a recepta- cle with the supporting fingers 16 and operat- ing handle 18 resting on the upper edge thereof, as best shown in Fig. 1 of the draw- 110

ings. If desired, however, the strainer may be supported in the hand by grasping the operating handle 18, as will be readily understood.

5 In order to clean the strainer it is merely necessary to loose the clamping screw 13 when the filtering medium may be readily detached and thoroughly cleaned by washing the same, said filtering medium being subsequently placed in position on the strainer, in the manner before described.

10 While it is preferred to use a filtering fabric in connection with the strainer it will of course be understood that wire gauze or netting may be substituted as a filtering medium if desired.

15 From the foregoing description it will be seen that there is provided an extremely simple, inexpensive and efficient device admirably adapted for the attainment of the ends in view.

Having thus described the invention what is claimed is:

1. A strainer including a rim, a filtering 25 medium extending transversely across one side of the rim, a split clamping band encircling the rim and bearing against the filtering medium, rods secured to the walls of the clamping band and having their free ends 30 terminating in laterally extending supporting fingers, and means independent of the supporting fingers for clamping the band in engagement with the rim.

2. A strainer including a rim, a filtering 35 medium extending transversely across the rim, a split clamping band encircling the rim and bearing against the filtering medium, spring rods secured to the clamping band and each having one end thereof extended 40 laterally to form diverging supporting fingers, the opposite ends of the rods being united to produce a shank, and a handle having a socket formed therein for the reception of the shank.

45 3. A strainer including a supporting rim having its upper and lower edges provided with a reinforcing bead, a filtering medium extending transversely across one side of the

rim, a split clamping band encircling the rim and bearing against the filtering medium, 50 rods secured to the clamping band and terminating in diverging supporting fingers, a handle secured to the band between said supporting fingers, and means independent of the fingers for clamping the band in engagement 55 with the filtering medium.

4. A strainer including a supporting rim, a filtering medium extending across the bottom of the rim, a split clamping band encircling the rim and bearing against the filtering 60 medium, the split end of said band being provided with laterally extending ears, a threaded pin secured to one of the ears and extended through an opening in the adjacent ear, a nut engaging the threads on the pin for 65 clamping the band in engagement with the filtering medium, diverging fingers extending laterally from the clamping band, in spaced relation to the ears and an operating handle carried by the band and disposed between 70 the supporting fingers.

5. A strainer including a rim, a filtering medium extending transversely across the bottom of the rim, a vertically split clamping band encircling the rim and engaging the filtering medium, brackets secured to the split end of the band and provided with laterally extending ears, a threaded pin secured to one of the ears and extending through an opening in the adjacent ear, a nut engaging the 75 threads on the pin, spring rods secured to the exterior walls of the clamping band and each having one end thereof extended laterally in spaced relation to the adjacent ear to form diverging supporting fingers, the opposite ends of the rods being united and extended laterally to produce a shank, and an operating handle having a longitudinal opening formed therein for the reception of said shank.

80 In testimony that I claim the foregoing as my own, I have hereto affixed my signature in the presence of two witnesses.

FLORENCE M. I. REEVE.
